(57) **CLAIM**

The ornamental design for a display board, as shown and described.

DESCRIPTION

FIG. 1 is a perspective view of a display board showing my new design;

FIG. 2 is a plan view of the display board of FIG. 1;

FIG. 3 is a side elevational view of the display board of FIGS. 1 and 2, the opposite side view being the mirror image;

FIG. 4 is a right side elevational view of the display board of FIGS. 1–3, the opposite side view being the mirror image;

FIG. 5 is a bottom view of the display board of FIGS. 1–4;

FIG. 6 is a perspective view of another embodiment of a display board showing my new design;

FIG. 7 is a plan view of the display board of FIG. 6;

FIG. 8 is a side elevational view of the display board of FIGS. 6 and 7, the opposite side view being the mirror image;

FIG. 9 is a right side elevational view of the display board of FIGS. 6–8, the opposite side view being the mirror image; and,

FIG. 10 is a bottom view of the display board of FIGS. 6–9.

The broken lines are for illustration only and form no part of the claimed design.
